UNITED STATES PATENT OFFICE.

WILHELM GRAAFF, OF BERLIN, GERMANY.

COOLING ATTACHMENT FOR ICE-MAKING MACHINES.

1,076,760.

Specification of Letters Patent.

Patented Oct. 28, 1913.

Application filed September 26, 1911. Serial No. 651,396.

To all whom it may concern:

Be it known that I, WILHELM GRAAFF, merchant, a subject of the German Emperor, and residing at 17 Linkstrasse, Berlin, W. 9, 5 in the Kingdom of Prussia, Germany, have invented certain new and useful Improvements in Cooling Attachments for Ice-Making Machines, of which the following is a specification.

10 The present invention relates to a cooling attachment for ice making machines and in particular for such machines which consists of two vessels communicating with each other serving alternately as still or absorber and 15 condenser or refrigerator, evacuated and hermetically sealed once for all, in which vessels the refrigerating medium travels to and fro under change of its aggregate form. A machine of this kind is for instance de- 20 scribed in the U. S. Patent 958,683. In these known machines the cooling of the absorber and refrigerator was hitherto effected by means of cooling water, which was allowed to run over these vessels. As with these 25 machines the production of ice lasts about one hour, the consumption of cooling water will be very considerable. Besides the duration of the ice making operation and the efficiency of the machine depends on the 30 temperature of the cooling water. Cooling water in sufficient quantity or of a sufficiently low temperature is, however, not always obtainable as for instance in tropical countries. The present attachment is in- 35 tended to obviate such difficulties, as it re- 40 quires a very small quantity of cooling liquid and will nevertheless produce a very effective cooling, by the cooling liquid being distributed in a very thin film over the ab- 45 sorber and refrigerator and then made to evaporate there by means of air blown on these vessels. The attachment essentially 50 consists of a multichambered box, which contains in one chamber the cooling liquid, 55 say water, which is applied in suitable manner—say by means of a strip of felt—to the vessel to be cooled. The other chambers are air chambers, from which the air is blown on to the vessel to be cooled and wetted with 60 the cooling liquid. In consequence thereof the cooling liquid will be rapidly evaporated and the absorber or refrigerator respectively will be intensely cooled. Instead of three 65 chambers and one anti chamber only the attachment may also be made with more cham- 70 bers, of which then several will be liquid chambers.

In the drawing a constructional form of the present invention is exemplified.

Figure 1 is an ice making machine fitted 60 with the attachment shown partly in section; Fig. 2 is a plan of the attachment and Fig. 3 is a sectional view along the line A—B in Fig. 1.

In the drawing *a* is the refrigerator and *b* 65 is the absorber of an ice making machine. Over the absorber *b* is arranged a casing *c* which is supported by the arms *d* which are joined at their rear ends and secured to a rod *e*, which is pivoted in a guide *f*, and is 70 longitudinally adjustable, so as to allow of swinging the casing *c* alternately over the absorber and the refrigerator.

The casing *c* contains the chambers *g*, *h*, *i*, *k*. Of these chambers *g* and *i* are air chambers 75 extending the whole length of the casing. The air enters into these chambers through slots *m* and *n* from the chamber *h*, into which it enters through a pipe *o*. The air escapes from the chambers *g* and *i* 80 through mouth pieces having slots *p* on to the refrigerator or the absorber. In the chamber *k*, which incloses the air chamber *h*, is contained the cooling liquid. A short tube *q* admits of filling the cooling liquid 85 into the chamber *k*. The cooling liquid is finely distributed over the surface of the absorber or refrigerator respectively. A strip of felt *r* or the like, which closes the chamber *k* which is open at the bottom has a slid- 90 ing contact with the vessel to be cooled.

The attachment operates in the following manner: The permanently moist strip of felt *r* transmits the cooling liquid from the chamber *k* in a thin film to the top of the 95 vessel to be cooled. Against this film of liquid, is blown compressed air, which has been produced in any suitable manner, the air entering through the slots *p*, whereby the liquid is made to rapidly evaporate and the vessel consequently is cooled.

I claim:

1. In a cooling attachment for ice making machines in combination a casing having a chamber for cooling liquid, and means for applying said liquid, in form of a thin film to the vessel to be cooled, air chambers in said casing, having longitudinal slits adapted to conduct the air against the vessel to be cooled, and an air supply pipe for said air 105 110

chambers whereby the liquid applied to the surface of the same is made to rapidly evaporate.

2. In a cooling attachment for ice making machines in combination a casing having a chamber for cooling liquid, air chambers in said casing adapted to conduct the air against the vessel to be cooled, an air supply pipe for said air chambers and a strip 10 of liquid absorbing material forming the closure at the bottom of said liquid chamber, said strip transmitting the cooling liquid in a thin film over said vessel and adapted to contact with the vessel to be cooled, 15 and means for directing an air blast against said vessel, thereby rapidly evaporating the film of cooling liquid.

3. In a cooling attachment for ice making machines having a refrigerator and an ab-

sorber, in combination, a casing having a 20 chamber for a cooling medium, a strip of felt forming the bottom closure of said chamber, said strip being made of liquid absorbing material adapted to distribute the cooling liquid in a thin film over the vessel 25 to be cooled, air chambers in said casing and a supply pipe therefor, said air chambers having mouth pieces for directing the air blast from said air chambers against said vessel, and a pivotal support for said attachment whereby it may be moved to a plurality of positions.

In testimony whereof I affix my signature in presence of two witnesses.

WILHELM GRAAFF.
